AIR CONDITIONING RADIATOR

Gilbert S. Horten, Tuxedo Park, N. Y.

Application June 12, 1939, Serial No. 278,746

3 Claims. (Cl. 98—106)

This invention aims to provide a novel means for regulating the delivery of air into a room, for the purposes of heating or humidifying. The flow of air is controlled by a closure member, and the invention aims to supply novel means for mounting and operating the closure member. The invention aims, further, to supply a casing of novel form, and to provide novel means for holding it in place.

10. It is within the province of the disclosure to improve generally and to enhance the utility of devices of that type to which the present invention appertains.

With the above and other objects in view, 15 which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

20. In the accompanying drawings:

25. Fig. 1 shows in front elevation, a device constructed in accordance with the invention;

Fig. 2 is a section on the line 2—2 of Fig. 1;

Fig. 3 is a section on the line 3—3 of Fig. 1;

30. Fig. 4 is a vertical section on the line 4—4 of Fig. 2;

Fig. 5 is a section on the line 5—5 of Fig. 2;

Fig. 6 is a vertical sectional view illustrating the means for securing the upper portion of the casing.

35. The drawings show the floor of a building, having an opening 2. On the floor is secured a base frame 3, having an opening 4 registering with the opening 2 in the floor. The base frame 3 has an upstanding rim 5 about its entire margin. The 40 base frame 3 is provided along the forward edge of the opening 4, and at the ends thereof, with a depending flange 6, fitting within the opening 2 in the floor. Along the rear edge of the opening 4, the base frame 3 is supplied with an upstanding lip 7, disposed parallel to the rear portion of the upstanding rim 5.

45. The numeral 8 designates a casing, having an opening 16 at the front, the casing being open at the bottom. The casing 8 is received at its lower 50 end within the upstanding rim 5 on the base plate 3, the lower part of the rear wall of the casing being received between the lip 7 and the rear portion of the rim 5. Any suitable means 55 may be provided for delivering air into the bottom of the casing 8. Securing elements 9 con-

nect the end members of the rim 5 of the base plate 3 with the end walls of the casing 8.

At its top, the casing 8 is supplied with a depending threaded stud 10. Along the top of the casing, near the front opening 16 thereof, extends 5 a depending flange 11. The casing 8 includes a downwardly extended front member 12, defining the upper edge of the front opening 16 in the casing. Attached to the front member 12 of the casing 8, and disposed behind it, is an elongated 10 guide 14, which is L-shaped in vertical transverse section, as Fig. 4 will show. There are vertical, inwardly extended wings 15 on the casing, at the ends of the front opening 16 of the casing.

A grating 26 is provided, and includes vertical 15 end rails 17, connected by horizontal louvers 18, which may have such downward and forward curvature as is desired. The end rails 17 of the grating 26 extend upwardly from the base frame 3 to the front member 12 of the casing 8, and to 20 the flange 11. The end rails 17 of the grating 26 are disposed between the wings 15 of the casing 8, and are connected thereto by securing elements 19.

A hanger plate 20 is provided, and is supplied 25 with a transverse, elongated slot 21, receiving the stud 10 on the top of the casing 8, the construction being such that the hanger plate can be adjusted forwardly and backwardly. The hanger plate 20 is held against the under-surface of the 30 top of the casing 8 by a nut 22 threaded on the stud 10. The hanger plate 20 is provided at the ends of its forward edge with suspension hooks 23, disposed close to the flange 11 on the top of the casing 8, and on the intermediate portion of 35 the forward edge of the hanger plate there is a depending, rectangularly disposed stop 24.

A closure plate 25 cooperates with the rear surface of the grating 26, to control the passage of air between the louvers 18, and is mounted at its 40 upper edge for swinging movement. At its upper edge, the closure plate 25 has a roll bead 27, containing a hinge rod 28, and in two places, the bead is cut away, as at 29 in Fig. 5, to receive the suspension hooks 23 on the hanger plate 20, 45 which engage the rod 28, and thus suspend the closure plate for swinging movement. The bead 27 of the closure plate 25 has engagement with the flange 11 on the upper part of the casing 8. To the rear surface of the closure plate 25 is 50 secured a vertical tubular socket 30, and in the closure plate there is a horizontally elongated slot 31, there being an opening 32 in the socket 30, behind the slot. A keeper pin 33 is held frictionally but securely in the socket 30.

A downwardly and rearwardly inclined, plate-like operating member 34, is mounted for horizontal sliding movement in the slot 31 of the closure plate 25 and extends through the opening 32 in the socket 30. An inclined slot 35 is formed in the closure plate 34, the keeper pin 33 on the closure plate 25 being received in the slot 35. Near its forward end, the operating member 34 has a depending finger piece 36, located accessibly with respect to the front of the casing 8. At its forward edge, the operating member 34 is supplied with a hook flange 37, slidably engaged with the horizontal part of the guide 14 on the casing 8 and held thereon by engagement with the front member 12 of the casing 8. The construction is such that the operating member 34 is mounted on the casing 8 for horizontal right line sliding movement.

The closure plate 25 is moved to and from open position, by reciprocating the operating member 34 through the instrumentality of the finger piece 36. Since the keeper pin 33 on the closure plate 25 is received in the inclined slot 35 of the operating member 34, the closure plate will be swung 25 backwardly and forwardly, from and to closed position with respect to the grating 26, an observation which will be understood readily when Fig. 3 of the drawings is examined. As the closure plate 25 swings backwardly and upwardly, the upper end of the socket 30 comes into contact with the stop 24 on the hanger plate 20, and, thus, the opening movement of the closure plate 25 is limited.

The device forming the subject matter of this application is simple in construction, but will be found thoroughly advantageous for the ends in view. Attention is directed to the fact that the article may be assembled and taken apart readily.

Referring to Fig. 6, should it be desired to mount the casing 8 in the plastering 38 on a wall 39, recourse may be had to an angular anchor 40, secured at 41 to the wall 39, and at 42 to the top of the casing 8.

Having thus described the invention, what is claimed is:

1. In a device for controlling the passage of air, a casing having an outlet and including a front member, a guide secured to the upper portion of the casing, a closure for the outlet and mounted 50 on the upper portion of the casing for swinging

movement, the closure having a horizontally elongated opening, a plate-like operating member movable horizontally with respect to the casing and comprising a part movable along the guide and held thereon by the front member, the operating member comprising an actuating element accessible at the outlet, the operating member having a slot inclined from the front part of the casing toward the back thereof, the slot-carrying portion of the operating member extending through the opening, and a keeper carried by the closure and extended through the slot.

2. In a device for controlling the passage of air, a casing having an outlet and including a front member, a guide secured to the upper portion of the casing, and having a flange extended toward the front member, a closure for the outlet and mounted on the upper portion of the casing for swinging movement, the closure having a horizontally elongated opening, a plate-like operating member movable horizontally of the casing and comprising a hook-shaped part movable along the flange and held thereon by the front member, the operating member comprising an actuating element accessible at the outlet, the operating member having a slot inclined from the front of the casing toward the back thereof, the slot-carrying portion of the operating member extending through the opening, and a keeper carried by the closure and extended through the slot.

3. In a device for controlling the passage of air, a casing having an outlet, a hanger having a depending stop, means for mounting the hanger on the top of the casing for adjustment toward and away from the outlet, a closure for the outlet and provided with a horizontally elongated opening, means for mounting the closure for swinging movement on the hanger, a tubular socket on the hanger and provided with an opening, the socket being engageable with the stop to limit the opening movement of the closure, a plate-like operating member having a slot inclined from the front of the casing toward the back thereof, means for guiding the operating member for horizontal movement on the casing, the operating member extending through the openings, and a keeper extended through the slot, the keeper being mounted in the socket.

GILBERT S. HORTON. 50
